UNITED STATES PATENT OFFICE.

OLIVER C. EARL, OF ALLEGHENY, PENNSYLVANIA.

DESIGN FOR AN EYE-PROTECTOR.

SPECIFICATION forming part of Design No. 34,131, dated February 26, 1901.

Application filed December 6, 1900. Serial No. 38,937. Term of patent 7 years.

To all whom it may concern:

Be it known that I, OLIVER C. EARL, a citizen of the United States of America, residing at Allegheny, in the county of Allegheny and 5 State of Pennsylvania, have invented and produced a new and original Design for Eye-Protectors, of which the following is a specification, reference being had therein to the accompanying drawing.

In the accompanying drawing the figure represents a perspective view of an eye-protector embodying my design.

The leading feature of my design consists in the ornamental configuration or shape, 5 and in the drawing the numeral 1 represents the peak, substantially semicircular, with the upper edge extending at substantially right angles to the body of the peak, forming a ridge 2. The lower edge 3 projects out-

wardly at an angle to the body, and at the 20 ends of the peak this projecting part 3 extends outwardly at right angles thereto, forming ends 4. The peak is provided with depressions 5 of oblong form, and arranged between these depressions and the ends of the 25 peak are raised ornamental scrolls 6.

Having thus fully described my invention, what I claim as new, and desire to secure by Letters Patent, is—

The design for an eye-protector, substantially as shown and described.

In testimony whereof I affix my signature in the presence of two witnesses.

OLIVER C. EARL.
